WARNING SIGNAL

Harold W. Edgar, Williamsville, N.Y.

Application October 13, 1958, Serial No. 52,952

Term of patent 14 years

(Cl. D72—1)

Fig. 1 is a front perspective view of a warning signal, showing my new design;

Fig. 2 is a rear elevational view thereof; and

Fig. 3 is a bottom plan view thereof.

The phantom lettering is for illustrative purposes only.

I claim:

The ornamental design for a warning signal, substantially as shown and described.
